(57) **CLAIM**

The ornamental design for a leaf game, as shown and described.

DESCRIPTION

FIG. 1 is a top perspective view of the leaf game in an assembled configuration;

FIG. 2 is a front view thereof;

FIG. 3 is a rear view thereof;

FIG. 4 is a side view thereof;

FIG. 5 is another side view thereof;

FIG. 6 is a top view thereof;

FIG. 7 is a bottom view thereof; and,

FIG. 8 is a top perspective view of the leaf game in an exploded configuration.

In some cases, there is a spherical cap at the top of the stem, as shown in FIGS. 1-6 and 8. In some implementations, all the leaves are detachable from the stem, as shown in FIG. 8. The broken lines in each figure illustrate portions of the leaf game that form no part of the claimed design.
